UNITED STATES PATENT OFFICE.

HENRY V. RAU, OF BROOKLYN, NEW YORK, ASSIGNOR TO EDWIN B. STIMPSON COMPANY, OF BROOKLYN, NEW YORK, A CORPORATION OF NEW YORK.

DESIGN FOR A LACING-HOOK.

52,544.

Specification for Design.

Patented Oct. 8, 1918.

Application filed April 26, 1918. Serial No. 231,045. Term of patent 14 years.

To all whom it may concern:

Be it known that I, HENRY V. RAU, a citizen of the United States, residing at Brooklyn, in the county of Kings and State of New York, have invented a new, original, and ornamental Design for Lacing-Hooks, of which the following is a specification, reference being had to the accompanying drawing, forming part thereof.

In the drawing Figure 1 is a perspective

view and Fig. 2 is a plan view of a lacing hook, showing my new design.

I claim:

The ornamental design for a lacing hook, as shown.

Signed at Brooklyn, in the county of Kings, and State of New York, this 20th day of April, 1918.

HENRY V. RAU.
